JOSEPH ROBINSON, OF NEW YORK, N. Y.

AUTOMATIC TRAIN-PIPE CONNECTER

Application filed April 11, 1921, Serial No. 460,435. Renewed December 6, 1928.

My invention relates to improvements in automatic train pipe connectors, and is directed particularly to the provision of an improved means for attaching the automatic connector to the car coupler, especially to the well known bottom operating Sharon car coupler widely used on various types of railway cars. My improvement comprises a novel form of lug which is either cast integral with the coupler or welded thereon, and a bracket by which the connector is attached to said lug in such a manner as to produce a powerful and rugged foundation for the automatic connector. The construction minimizes the shearing strains upon the bolts which secure the bracket to the lug, and reduces the back lash or play which usually develops in the connection between the bracket and the lug in the present types of lugs and brackets for automatic connectors.

While the Sharon bottom operating car coupler leads, perhaps, all others in point of number in use, especially on passenger cars, it is the most difficult of the several to which 25 to apply an automatic connector. This is due to the peculiar form of operating lever used to open the knuckle of this coupler. It comprises a link or member which projects from the bottom of the coupler downwards approximately ten inches from the under side of the coupler shank. The lever leaves the coupler head at the exact place where the lugs to receive the automatic connector should be located. It is essential to the continued satisfactory operation of the connector that the lug therefor be located on the vertical center line of the coupler. But to thus attach the lug without interfering with the carrier iron by which the coupler is supported on the car, 30 and without interfering with the efficiency of the connector or the standardization of the parts thereof which should be interchangeable, has proved very difficult. It has forced the various designers in this art to attach the lug to one side of the coupler head, usually about three inches laterally of the vertical center line of the coupler. This location has necessitated the use of a bracket having a pronounced offset laterally resulting in excessive twisting and bending strains in the

bracket, especially in the forks thereof which span the lug, when the connectors couple up. Several years of experience, on a large number of cars, has proved that it is impossible to maintain a proper connection between the 55 coupler lugs and this offset style of bracket, or to maintain the connector in proper position with respect to the pulling face of the coupler when carried by such a bracket. This experience with these difficulties has led to the 60 development of the present improvement by which a powerful and rigid foundation for supporting the connector with respect to the coupler is provided.

My invention resides in the mechanism illustrated in the accompanying drawings, in which

Figure 1 is a side elevation of the well known Sharon bottom operating car coupler provided with my improvement, and

Figure 2 is a front elevation thereof. In this view a portion of the coupler is broken away and the link 3 is removed to illustrate more clearly the connection between the coupler and my improved lug. Both the lug B 75 and the bracket C of my improvement are shown in this view in elevation, and the automatic connector is omitted.

Referring now to the drawings: The well known Sharon bottom operating car coupler is illustrated at A. It is provided with a vertically extending lever or link 3 which is adapted to be shifted upwardly in the coupler head to open the knuckle 4. This operation of the link 3 is accomplished by any one of the several types of operating levers 5 employed at the end of the car to shift the link 3 in the usual manner. The link 3 extends from within the coupler head downward on approximately the vertical center line of the 80 coupler and is guided therein by projections 6 and 7 which lie on either side of the link and are formed integral with the coupler head. The operating lever mentioned is usually attached to a crank arm 8 as at 9 which crank arm is pivoted to the coupler head at 10 and operates through its connection 11 with the link 3 to lift the link when the operating lever 5 is pulled by the trainmen as aforesaid. My improved lug B is 100

cast or forged of any suitable material, preferably steel and is provided at its upper end with a forked head comprising prongs or side walls 12 and 13 joined at their rear by a 5 rear wall 14, as shown. The forked head spans the projections 6 and 7 and is shaped to conform approximately to the under side of the coupler head at the point where it is secured to the coupler, the upper edges of the 10 walls 12, 13 and 14 being tapered or bevelled away from the coupler head to facilitate welding the lug to the coupler, as shown at 15, 16 and 17. This construction insures that the metal in these walls will properly fuse 15 with the adjoining metal of the coupler A when welding the lug thereto. Any of the well known methods of welding, such as the acetylene process, may be used in this welding operation, the tapering of the walls 20 aforesaid affording a substantial space to receive the filling rod or flux used in the process. In the drawings the metal of the weld is illustrated only at certain points, it being omitted from other points of the lug, and adjacent 25 surfaces of the coupler, in order to more clearly illustrate the formation of the lug. It is to be understood that the weld extends from the forward point of the prong 12 around to the forward point of the prong 13, 30 thus encompassing the entire bevelled surfaces 15, 16 and 17, affording a large rugged weld. At 18, 19 and 20 I have indicated how the weld would appear in section at these 35 points.

Extending downwardly on the vertical center line of the coupler, and approximately midway between the prongs 12 and 13, the lug is provided with a base or tongue 21 which lies immediately behind the link 3 with its 40 vertical inner edge paralleling the link as shown particularly in Figure 1. The rear or outer edge of the base 21 is inclined or cut away as at 22 to clear the usual carrier iron H by which the coupler is supported on the car. To the base of the lug I attach my 45 improved bracket C as by means of bolts 23 and 24, the upper end of the bracket being provided with vertically extending portions or ears 25 and 26 forming a fork which spans the lug B and through which these bolts extend. It will be observed that two of the bolts are 50 placed one above the other in the same vertical plane and that the distance between their centers is approximately half the distance from the center of the lower bolt 24 to the center of the universal joint formed by the vertically 55 extending elongated projection 28 of the bracket C and by the pivot device 27 mounted thereon.

This arrangement shortens the power arm of the bracket with respect to the bolts 23 and 24 to such an extent that comparatively small 60 bolts may be used with safety. This is a most important advantage and one not attainable 65 where the lug is located as in Figure 2, since

that location permits the use of only a very short lug on which there is not sufficient room to properly space the bolts. The result is a weak and unsatisfactory foundation for the automatic connector. A lug produced according to my improvement also facilitates manufacture inasmuch as it permits considerable variation in the size of the holes in the lug and the bracket C without causing an objectionable amount of back lash between these parts. This desirable advantage is particularly important when the lug is cast integral with the coupler, as it is practically impossible to accurately core these comparatively small holes in a steel casting the size of a 80 car coupler.

The lower portion of my improved bracket C is offset forward so as to project under the bottom of the link 3 and bring the coupling head E of the automatic connector in the position required, with respect to the pulling face of the coupler A, to insure that the proper compression of the buffer or supporting spring F of the connector will be had upon the coupling of the cars. The bracket C terminates at its lower end in the aforesaid elongated projection or anchor device 28, having formed on its front face a curved or flared seat 29 adapted to receive the complementarily curved or flared forward inner wall 30 of the perforated head 31 of the pivot device 27. The projection 28 is located on the vertical center line of the bracket C, is powerfully braced at 32, and is provided with an overhanging portion 33 which serves to maintain the pivot device thereon, and co-operates with the pivot device to support the connector on the bracket C. The universal joint formed by the projection 28 and the pivot device 27 lies directly below the lower end of the link 3 and in approximately the same vertical plane, as shown, but it may of course be otherwise located if found desirable.

Any suitable form of coupling head may of course be carried by my improved bracket and lug, I show a well known type of head E having a pipe or body G which extends rearwardly therefrom and embraces or spans the projection 28 of the bracket, and terminates in a flange 34 normally held in engagement with the wide rear face 35 of the bracket by the spring F. The forward end of the spring rests against the flange 34 while an abutment 36 threadingly mounted upon the pivot device 27, supports the rear end thereof and serves to maintain the spring under the required compression. It will be observed from Figure 2 that the sides of the base 21 of the lug, and the inner walls of the ears 25 and 26 of the bracket C are tapered. This is to facilitate the manufacture and assembly of these parts and to give maximum strength to the base 21 at its upper end.

The importance to the railways of providing a rigid and powerful foundation for the 130

automatic connector in applying it to their cars becomes evident when it is remembered that with the continued developments in the air brake and heating apparatus of present day railway equipment, the buffer spring F may need to be made considerably heavier in order to hold the increased fluid pressures. In this event great loss would result if the lugs B and the bracket C should have to be replaced because insufficiently strong and rugged to withstand the force of the heavier spring, and the attending strains of service. That experience has already been encountered in some instances and the loss, even at this early period in the use of automatic connectors, has amounted to many thousands of dollars. My improvement effectually provides against the reasonable possibility of this difficulty arising inasmuch as it provides a powerful and rugged foundation for the connector, and is so located on the car coupler as to minimize the destructive strains of service upon its parts, thus insuring maximum life and stability.

25 What I claim is:

1. In an automatic train pipe connector, the combination with a car coupler having a vertically extending link adapted to move vertically in the coupler head, of a lug for supporting said connector on said coupler, said lug being provided with a pair of vertically extending forwardly projecting walls lying one on either side of said link and rigidly secured to said coupler head.

35 2. In an automatic train pipe connector, the combination with a car coupler having an opening in its lower side of a link adapted to reciprocate vertically in said opening, and means for attaching an automatic connector to said coupler, said means comprising a lug having forwardly extending vertically disposed projections embracing said link and rigidly secured to said coupler, a vertically disposed base attached to said projections and extending downwardly therefrom, and a bracket secured to said base and carrying said connector.

50 3. In an automatic train pipe connector, the combination with a car coupler having an opening in its lower side, of a link adapted to reciprocate in said opening, and means for attaching an automatic connector to said coupler, said means comprising a lug having a forked head embracing said link and shaped to conform approximately to the contour of the coupler at the point where it is applied thereto, the upper edges of said forked head being inclined away from the coupler to facilitate attachment of the lug to the coupler,

55 a vertically disposed base formed integral with said forked head between the prongs thereof, and a bracket spanning said base, and rigidly clamped thereto.

60 4. In an automatic train pipe connector, the combination with a car coupler having

an opening in its lower side, of a pair of vertically disposed projections flanking said opening and formed integrally with said coupler, a link adapted to reciprocate vertically in said opening between said projections, and means for attaching an automatic connector to said coupler, said means comprising a lug having a pair of vertically disposed forwardly projecting portions joined at their rear ends forming a fork into which said vertically disposed projections extend, one of said forwardly extending portions lying on either side of said link, a vertically disposed base connected to said portions, a bracket attached to said base and having at its lower end an elongated projection provided with a flared or curved seat adapted to permit universal movement to said connector.

65 5. In an automatic train pipe connector, the combination with a car coupler suitably supported on a carrier iron and having an opening in its lower side, of a link adapted to reciprocate in said opening, and means for attaching an automatic connector to said coupler, said means comprising a lug having a forked head embracing said link and shaped to conform approximately to the contour of the coupler at the point where it is attached thereto, the upper edge of said forked head being beveled to facilitate attachment to the coupler, a tapered vertically disposed base formed integral with said forked head between the prongs thereof and having its rear side cut away to clear said carrier iron, a bracket having a forked upper end into which said base extends, the inner walls of said forked upper end being inclined to agree with the taper of said base, and means for clamping said forked end rigidly to said base.

70 6. In an automatic train pipe connector, a combination with a car coupler having an opening in its lower side, of a link adapted to reciprocate in said opening, and means for attaching an automatic connector to said coupler, and means comprising a lug having a forked head embracing said link and shaped to conform approximately to the contour of the coupler at the point where it is applied to the coupler, the upper edges of said forked edge being inclined away from the coupler to facilitate attachment thereof to the coupler, a base formed integral with said forked head between the prongs thereof and depending downwardly therefrom in the vertical plane immediately behind said link, a bracket forked at its upper end to receive said base and terminating at its lower end in a vertically disposed elongated projection provided with a curved seat to support said automatic connector and to permit universal movement thereto, said bracket being offset between its forked upper end and said elongated projection to carry said projection forward under the lower end of said link, and means to rigid-

ly clamp the forked end of said bracket to said base.

7. A construction of the kind described comprising, in combination, a car coupler having an opening in its lower side, a bracket secured to said car coupler, means carried by said bracket for supporting an automatic connector, a link adapted to reciprocate in the opening in said car coupler, said bracket at its upper end having upwardly projecting spaced portions which lie on opposite sides of said link, and which are secured to said car coupler on opposite sides of said opening.

8. A construction of the kind described comprising, in combination, a car coupler having an opening in its lower side, a projection arranged on each side of said opening and extending downwardly from said coupler, a link adapted to reciprocate in said opening between said projections, a bracket secured to said coupler, said bracket at its upper end having upwardly projecting spaced portions which embrace said link and said projections on the car coupler, and means carried by said bracket for supporting an automatic connector.

9. In combination with a hollow car coupler having an opening in the bottom thereof and a link extending downwardly through said opening, said coupler having a projection arranged on each side of said opening and extending downwardly from said coupler, a bracket secured to said coupler and extending downwardly therefrom, said bracket at its upper end having upwardly projecting spaced portions rigidly secured to said car coupler and spanning said projections thereon, and means carried by said bracket for supporting an automatic train pipe connector.

In testimony whereof I affix my signature.
JOSEPH ROBINSON.
